UNITED STATES PATENT OFFICE

123,407

DESIGN FOR A SOAP CAKE OR SIMILAR ARTICLE

Juanita H. Leonard, New York, N. Y., assignor to Harriet Hubbard Ayer, Inc., New York, N. Y., a corporation of New York

Application March 13, 1940, Serial No. 90,871

Term of patent 3½ years

To all whom it may concern:

Be it known that I, Juanita H. Leonard, a citizen of the United States, residing in the city, county, and State of New York, have invented a new, original, and ornamental Design for Soap Cakes or Similar Articles, of which the following is a specification, reference being had to the accompanying drawing, forming a part thereof, in which:

Figure 1 is a top plan view of a soap cake or similar article, showing my new design;

I claim:

The ornamental design for a soap cake or similar article, as shown.

JUANITA H. LEONARD.
